UNITED STATES PATENT OFFICE.

JAMES A. WATKINS, OF DETROIT, MICHIGAN, ASSIGNOR TO AMERICAN BLOWER COMPANY, OF DETROIT, MICHIGAN, A CORPORATION OF MICHIGAN.

CENTRIFUGAL FAN.

Application filed October 6, 1920, Serial No. 414,987. Renewed November 20, 1922.

To all whom it may concern:

Be it known that I, JAMES A. WATKINS, a citizen of the United States, residing at Detroit, in the county of Wayne and State of Michigan, have invented certain new and useful Improvements in Centrifugal Fans, of which the following is a specification, reference being had therein to the accompanying drawing.

- 10 This invention relates to improvements in centrifugal fans and has for its object to provide an improved method of discharging air from the wheel into the atmosphere, and to simplify and increase the efficiency of 15 such devices; to provide an improved centrifugal fan having an efficient peripheral discharge extending all around the same, the necessity for the scroll volute auxiliary housing customarily employed with centrifugal fans to enclose the same and direct the 20 air flow, being entirely avoided.

Experience has shown in discharging air from the ordinary multi-blade centrifugal fan, the air does not have a sufficient velocity when it leaves the wheel, to force it away 25 from the wheel far enough to allow it to diffuse without agitation, that is, the air starts to diffuse immediately upon leaving the wheel, so that the strata of air around the 30 wheel is comparatively dense and the succeeding particles are hindered in leaving the wheel, thereby causing considerable agitation.

When the air is given sufficient directive 35 velocity the diffusion takes place a considerable distance from the wheel so that less disturbance is caused at the exit of the blades and consequently a more efficient wheel is obtained. This result is obtained 40 by the present invention, an important novel characteristic of the invention residing in the provision of an outer annular converging nozzle part constructed and arranged to form a substantial continuation of the 45 shrouding of the wheel and to conform to the path of the air, as it would leave the wheel under open discharge conditions, said annular nozzle part effecting no material change in the direction of the air, but acting 50 to simply continue the convergence to such a point as to give it sufficient directive velocity, and at this point to effectively discharge the same.

The invention, with other objects and ad-

vantages thereof, and the particular construction, combinations and arrangements of parts comprising the same, will be understood from the hereinafter contained detailed description when considered in connection with the accompanying drawings 55 forming part hereof, and wherein is illustrated several embodiments of the invention.

In the drawings:

Figure 1 is a vertical central section of a centrifugal fan constructed in accordance 60 with the present invention.

Figure 2 is a front elevation of one-half of the wheel illustrated in Fig. 1, with a part of one end plate broken away and the 65 blade shown in section.

Figure 3 is a vertical central section of a modification of the construction shown in Figs. 1 and 2.

Figure 4 is a vertical central section illustrating the application of the invention to a 70 different type of fan wheel.

Figure 5 is a front elevation, with parts in section, of the construction illustrated in Fig. 4.

Figure 6 is a side elevation with parts in 75 section illustrating a different form of mounting and use of the fan construction illustrated in Figs. 1 and 2.

Figures 7 and 8 are detail views of the 80 blades.

While I have illustrated in the drawings constructions in which only two different types of fan wheel are employed, it will of course be understood that the invention is applicable to the various other types of fan 85 wheels, that variations and changes in the particular constructions illustrated, and the carrying out of the invention in other forms, as will appeal to those skilled in the art and falling within the scope of the appended 90 claims, may be practiced without departing from the principles of the invention.

In Figs. 1 and 2 of the drawings, a fan wheel structure is shown of the kind described in the patent to F. R. Still No. 100 1,094,031, dated April 21, 1914. The wheel shown comprises a cast hub *d* having the usual conoidal flange *e*, to which is attached the usual flat sheet wheel disk *f*. To this disk are attached the blades *g*, and to the 105 front edges of the blades is secured a cone disk *h*, the inner edge *h'* of which is turned outwardly to form a flange, being of larger

diameter than the eye a . The blades g are secured in any suitable manner to the disk f and the cone disk h . In the present instance the blades are shown provided with tenons 5 or integral projecting portions g' entering recesses provided in the disk f and disk h . In the particular construction shown the blades are sixteen in number, although the number of blades may be varied according to the size 10 of the fan. The inner part v of each blade is radial, or closely approximates to a plane radiating from the axis. The blade is then curved in preferably a segment of a cylinder, this curved portion being lettered w , and 15 the outer portion x is plane or approximately so, and extends in a direction diverging by an angle y from the plane z , z —of the radial portion v of the blade. The curved portion w is a segment of a cylinder developed around a center or axis u (Fig. 2). The inner edge t of each blade is oblique to the axis, as shown in Fig. 1, so that the blade widens as it recedes from the inlet. The wheel is designed to revolve in the direction of the arrow i in Fig. 2; hence, the 20 blades are curved forwardly so that their outer or discharging end portions x occupy planes tangential to a circle smaller than the circumference of the wheel. 25 While, as will be understood, the proportions for the wheel may be varied to meet different conditions, proportions that have been found to be especially satisfactory are as follows, being stated with relation to the 30 radius of the fan wheel as unity:

The axial width of the blade at its inner or inlet side is .57, and at its outer or discharge side is from .40 to .50; the radial dimension of the blade is .32 at the front or 35 inlet side and .50 at the rear or disk side. The radial portion v of the blade has an extreme length of .22; the portion x has a length of .0625; the radius of the curved portion w is .25. A feature of great importance is the angle y which should closely 40 approximate 60 degrees. The distance from the tip of one blade to the back of the next preceding one (measured on the line j , u , Fig. 2) should approximate the space between the blades at their inner front edges. 45

In accordance with the teachings of the present invention, an annular peripheral discharge nozzle is provided, the volute scroll housing customarily employed being eliminated. In the particular embodiment of 50 the invention illustrated in Figs. 1 and 2, the annular nozzle 1 is constructed as a part of the fan wheel for rotation therewith. Said nozzle is formed by annular extensions 55 of the wheel shrouding or the outer portions of the disks f , h , the extensions having converging wall portions and outer marginal diverging lip portions providing a somewhat restricted intermediate nozzle portion 60 with an enlarged outlet portion. The annu-

lar extensions of the disk f have an inner portion 2 extending at an inward inclination, and an adjoining part 3 extending at an outward inclination at an angle about equal to the angle of inclination of the part 2. 70 The extension 4 of the coned disk h is shown extending at the same angle as the angle of the coned face of the conical disk. 5, 6 designate the marginal lip portions, the lip portions being shown flaring outwardly on a 75 slight curve.

The nozzle 1, which constitutes a substantial continuation of the shrouding of the wheel, is shaped to conform to the path of the air as it would leave the wheel under 80 open discharge conditions. In this way no material change in the direction of the air is effected, the nozzle simply acting to continue the convergence of the air to such a point as to give it sufficient directive velocity, and at this point providing an efficient discharge of air. 85

The invention in its broader aspect comprehends such modified constructions as indicated in a general way in Fig. 3 of the 90 drawings, in which the annular peripheral nozzle part is constructed as a separate part from the fan wheel and is stationary with reference thereto. In this structure 7 designates the fan wheel and 8 the annular 95 nozzle, the latter, in this instance, being mounted on any suitable form of support (not shown).

In Figs. 4 and 5 of the drawings the invention is shown applied to a multi-blade 100 type of wheel, the wheel being shown as comprising a hub 9, end plates 10, 11 and blades or fans 12. 13 designates the annular peripheral nozzle formed by extensions of the shrouding or outer portions of the end 105 plates 10, 11. The nozzle part has inwardly converging wall portions, and outwardly flaring marginal lips. In this instance, the walls 14, 15 of the extensions both extend inwardly from the wheel shrouding to the 110 marginal lip portions 16 and 17, the wall 14 extending at a greater angle than the wall 15.

It will be noted that the constructions hereinbefore described are such as to provide an efficient peripheral discharge, the necessity for the usual auxiliary housing being entirely avoided and a more simple advantageous centrifugal fan structure afforded. Those forms of the device in which 115 the annular nozzle part rotates with the fan wheel also possess the advantage that the skin friction through the fan is materially reduced, thereby reducing the skin velocity of the air under pressure. Fans constructed 120 in accordance with the present invention are adapted for general purposes, but have been found especially valuable for gas engine cooling. My improved fan is also particularly advantageous for use as a desk fan for 125 130

offices, and for dining room tables, being more efficient than the ordinary four-blade propeller desk fan. It is especially advantageous over the ordinary desk fan in throwing the air in all directions and is not dependent upon and does not require oscillating mechanism. Furthermore, owing to the particular nature of the discharge, the operation of the fan will not disturb papers on the desk or cool the food.

5 An exemplification of the adaptation of my improved fan to this use is indicated in a general way in Fig. 6.

In this figure, 20 designates the fan wheel 15 and 21 the annular nozzle part, the wheel being mounted on a vertical shaft 22. 23 designates a suitable motor.

What I claim is:

1. A centrifugal fan consisting of an un- 20 enclosed fan wheel provided with an open annular peripheral discharge nozzle extending beyond the delivery end portions of the blades and rotatable with the fan wheel.

2. A centrifugal fan consisting of an un- 25 enclosed fan wheel provided with an open annular peripheral discharge nozzle rotatable with the fan wheel, said discharge nozzle extending beyond the delivery end portions of the blades and having opposing 30 annular outwardly converging walls.

3. A centrifugal fan consisting of a fan wheel provided with an open annular peripheral discharge nozzle rotatable with the fan wheel, said discharge nozzle having an 35 annular constricted portion with an adjoining enlarged outlet portion.

4. A centrifugal fan consisting of a fan wheel provided with an open annular peripheral discharge nozzle rotatable with the 40 fan wheel, said nozzle having opposing annular outwardly converging walls, and adjoining outwardly diverging wall portions.

5. A centrifugal fan consisting of an un- 45 enclosed fan wheel provided with an open annular peripheral discharge nozzle rotatable with the fan wheel, said discharge nozzle being formed by oppositely disposed annular plate portions extending beyond the outer ends of the blades of the wheel.

50 6. A centrifugal fan including a fan wheel comprising a flat back-disk section disposed at right angles to the axis of the wheel, a front coned ring, blades between the disk and ring, said back-disk section and coned ring having opposing outer peripheral extensions forming an annular nozzle part.

7. A centrifugal fan including a fan wheel comprising a flat back-disk section 60 disposed at right angles to the axis of the wheel, a front coned ring, blades between the disk and ring, said back-disk section and coned ring having opposing outer peripheral extensions forming an annular nozzle part, 65 said back-disk section having an inner an-

nular portion extending at an inward inclination, and an outer portion extending at an outward inclination.

8. A centrifugal fan including a fan wheel comprising a flat back-disk section disposed 70 at right angles to the axis of the wheel, a front coned ring, blades between the disk and ring, the back disk section and coned ring having opposing outer peripheral extensions forming an annular nozzle part, 75 the back disk extension having an inner annular portion extending at an inward inclination and an outer portion extending at an outward inclination, and the said extension of the coned ring extending at an inward inclination at the angle of the coned ring.

9. A centrifugal fan including a fan wheel comprising a flat back-disk section disposed 80 at right angles to the axis of the wheel, a front coned ring, blades between the disk and ring, said back-disk section and coned ring having opposing outer peripheral extensions forming an annular nozzle part, 85 with an enlarged annular outlet part.

10. A centrifugal fan including a fan wheel comprising a flat back-disk section disposed at right angles to the axis of the wheel, a front coned ring, said back disk section and coned ring having opposing outer 90 peripheral extensions forming an annular nozzle part, said back-disk extension having an inner annular portion extending at an inward inclination, and the said extension of the coned ring extending at an inward inclination at the angle of the coned ring, and the coned ring and back-disk section having outer annular diverging outlet portions.

11. A centrifugal fan wheel consisting of a back disk and front ring with blades arranged therebetween, the inner portions of said blades occupying radial planes for a distance of approximately one-fifth the radius of the wheel, the outer or tip portions occupying oblique planes for a distance approximately one-sixteenth the radial dimension of the wheel, said planes being approximately sixty degrees from said radial planes, and the intermediate portions of the blades curved in approximately the segment of the cylinder having a radius about one-half the radius of the fan wheel, said back disk and front ring having opposing outer peripheral integral extensions forming an annular nozzle part.

12. A centrifugal fan wheel consisting of a back disk, a front coned ring, and blades therebetween, the radial dimension of the blades at said disk approximating one-half the radius of the wheel and at said ring approximating one-third such radius, their inner edges being inclined to the axis and their outer edges approximately parallel therewith, their inner axial dimension being approximately seven-tenths, and their outer 130

axial dimension being from four to five tenths the radial dimension of the wheel, the inner portions of the blades occupying radial planes, and the blades being then 5 curved forwardly, and terminating in oblique tip portions, said back disk and front coned ring having peripheral integral extensions forming a constricted annular nozzle part.

10 13. A centrifugal fan wheel consisting of a back disk and front ring, and blades arranged therebetween, the blades at their inner portions approximating to radial planes, their outer or tip portions occupying oblique 15 planes for a distance approximating one-tenth the radial dimension of the wheel, and their intermediate portions curved in ap-

proximately the segment of a cylinder, said back disk and front ring having opposing outer peripheral integral extensions forming 20 an annular nozzle part.

14. A centrifugal fan consisting of an unenclosed fan wheel having end plates and blades therebetween and provided with an open annular peripheral discharge nozzle 25 formed by integral annular extensions of the end plates beyond the outer ends of the blades.

In testimony whereof I hereunto affix my signature in the presence of two witnesses. 30
